ADJUSTABLE BED TABLE WITH CONTROLS
THEREFOR AT TABLE LOCATION

Alexander Grace, Agincourt, Ontario, Canada

Application October 23, 1951, Serial No. 252,603

3 Claims. (Cl. 311—27)

1

This invention relates to improvements in tables for hospital beds and for use in the home for invalids or persons confined to bed.

The principal object of the invention is to provide a bed table as aforesaid which can be conveniently adjusted by the user to any position to suit him and will securely hold its adjusted position to afford firm support to take the weight of an object or the user himself when shifting position.

Another important object is to provide a table which will fit substantially all beds and when not in use can be conveniently stored against the underside of the bed clear of the floor and when required can be instantly brought up at either side of the bed and quickly adjusted to the desired position.

The principal feature of the invention consists in mounting a table supported for horizontal movement transversely of the bed and for adjustable movement about mutually perpendicular, normally horizontal and vertical axes on a slide or carriage movable transversely of the bed frame beneath the bed and providing a connection between the slide and table support to permit the table and support to be swung to a position supported in suspension beneath the bed frame or to be carried to and brought up at either side of the bed.

A further feature consists in constructing the table support extending at right angles to the travel of the slide or carriage so that it is extensible to provide height adjustment for said table.

These and other objects and features will become apparent from the following description taken in conjunction with the accompanying drawings in which

Figure 1 is a transverse section of a bed having a table embodying the invention secured thereto.

Figure 2 is a vertical section on line 2—2 of Figure 1.

Figure 3 is a part elevational part sectional detail of the connection between the extensible support arm and lateral slide or carriage arm.

Figure 4 is an elevational detail of the extensible support arm showing the locking latch therefor.

Figure 5 is a part elevational part sectional detail of the connection between the extensible arm and table-carrying arm.

Figures 6 and 7 are plan and elevational details of the brake joint in the table-supporting arm.

Figure 8 is a sectional detail of the table assembly taken on the line 8—8 of Figure 9.

2

Figure 9 is a transverse section of the table assembly on line 9—9 of Figure 8.

With reference to the drawings, Figure 1, 1 represents the longitudinal side rails of a bed frame supporting springs 2 and mattress 3 represented in diagrammatic form.

Carried from the rails 1 by channel brackets 4 is a tube 5 extending transversely of the bed frame and supported therebeneath to form a trackway in which a tube or carriage 6 slides. 10 The tube 5 has a slot 7 in its underside. The slide or carriage 6 carries a depending vertical shaft 8 extending through the slot 7 and having a head 9 formed thereon or secured thereto.

Received on the shaft 8 between the head 9 and a collar 10 is the collar 11 of a horizontal shaft 12 free to rotate in a horizontal plane but lockable in adjusted positions by locking screw 13 adapted to enter notches 14 in the shaft 8.

20 An extensible support comprising a shaft 15 and a sleeve 16 slidably mounted thereon is mounted to rotate on the shaft 12 by the collar 17 secured to the end of shaft 15 and rotating between head 18 and collar 19 of the shaft 12 and locked by set screw 17'.

The sleeve 16 is provided with a slot 20 registering with a series of notches 21 formed in the shaft 15. A latch 22 pivoted to the end of a lever 23 and sliding on an abutment 24 is urged by spring 25 into the slot 20 to enter a selected notch 21 to maintain the shaft 15 and sleeve 16 in desired position of extension. Lever 23 is pivoted intermediate its length at 26 and is operated by a cord 27 which can be controlled from above the bed by the person using the table.

30 A pull on cord 27 will swing the lower end of latch 22 downwardly and inwardly and the latch in sliding on its abutment 24 will move outwardly at the upper end to clear the notches 21.

The upper end of the sleeve 16 has secured thereto a socket 28 provided with a lateral extension 29. The socket receives the head 30 of a U-shaft 31 with the plug 32 threading into the socket to maintain the shaft locked in position.

40 A plunger 33 mounted in the extension 29 and urged inwardly by spring 34 engaging between the end wall of the extension 29 and the fixed collar 35 on the plunger engage in notches 36 formed in the head 30 to lock the U-shaft in different positions of rotation.

The end of shaft 31 is reduced at 37 to form a rectangular tongue pivoted between the forked end 38 of the table bar 39. The table bar is adapted to jack-knife about its pivot 40 into 50 adjacent relation to the extensible support 16—16

when the table is to be stored, and when the table is in normal use above the bed a lock pin 41 inserted through the tongue 37 and forked end 38 locks the bar in a horizontal position.

Mounted on table bar 39 is a slide 42 which carries the turn-table 43 rotating about the axis of the table bar 39. The slide 42 and turn-table 43 can be locked in adjusted positions by set screws 44 and 45 respectively.

Carried on the turntable is a holder 46 provided with an upwardly and inwardly extending flange 47 beneath which the table surface or board 48 is received. Spring-urged balls 49 lock the table board in position.

The particular form of board and table holder disclosed are rectangular form but may be made circular where it is desired that the table itself rotate in its holder.

With a table such as described it will be appreciated that a person in bed can orient the table at any angle through the turntable 43 and can move it transversely of the bed by moving the slide 42 on its bar 39.

A cord 50 leading from the plunger 33 to a position adjacent the table permits the head 30 of shaft 31 to be released to swing the table bar about a vertical axis out of the way or to a position directly over the bed.

Additionally, through operation of the cord 27, which is brought up adjacent to the table, the person in bed can release latch 22 to adjust the table height.

When the table is to be stored beneath the bed the plunger 33 is released to swing the table bar from the position of Figure 1 through 90°, then 35 with the table moved towards the pin 41 the pin can be removed to swing the table bar downwardly against the extensible support formed by shaft 15 and sleeve 16. Then upon threading out locking screw 17, after moving the whole assembly 40 outwardly from the side of the bed rails 1 on the slide or carriage 6, the whole assembly can be swung about the horizontal axis of the shaft 12 to a position beneath the bed frame, and upon threading out locking screw 13 the whole assembly 45 rotated about the vertical axis of shaft 8 to the position of Figure 1.

From the stored position it will be appreciated that the slide 6 can be moved to bring the table assembly up at either side of the bed frame. This is convenient where one side of the bed must be placed against a wall or some other obstruction.

With a bed such as described complete manipulation by the patient is readily obtained to adjust the height, position and angle of the table above the bed. The collapsing and storage of the table beneath the bed frame, while not possible from above the bed, can be very readily accomplished by removal of the pin 41 and releasing the locking screws, locking shafts 12 and 15.

While the value of such universal movement and ready control of the table will be fully appreciated, it will be understood that various changes in mechanical detail may be made without departing from the scope of the appended claims.

What I claim as my invention is:

1. In a bed table device, the combination with a bed frame, of post means, means movable transversely beneath said frame supporting said post means for movement about two mutually perpendicular axes to enable said post means to swing from a substantially horizontal position to an upright position at either side of said frame, said post means being extensible, means locking said post means in selectable positions of extension, a table supporting arm carried by said post means and rotatable about the axis of said post means to swing between positions at the side and above said bed frame, means locking said arm in selectable positions of rotation, a table adjustably mounted on said arm, means at the location of said table for locking said table in adjusted positions relative said arm, and means operable from the location of said table for controlling said post and arm locking means.

2. A device as claimed in claim 1 in which said means supporting said post means comprises a track mounted beneath said bed frame to extend transversely thereof, a carriage on said track, a vertical post carried by and extending downwardly from said carriage, a horizontal post swingable about the axis of said vertical post carried by said vertical post, and means supporting said post means from said horizontal post for rotation about the axis of said horizontal post, and means adapted to lock said horizontal post and said post means against movement about their axes of swing.

3. A device as claimed in claim 2 in which said track comprises a tube extending transversely beneath said frame and having a slot in its underside and said carriage comprises a member slidably received within said tube with said vertical post carried thereby extending through said slot.
